UNITED STATES PATENT OFFICE.

JOSEPH W. DAWSON, OF ST. LOUIS, MISSOURI, ASSIGNOR TO BARRY-WEHMILLER MACHINERY COMPANY, OF ST. LOUIS, MISSOURI, A CORPORATION OF MISSOURI.

BOTTLE-WASHING APPARATUS.

1,212,747.

Specification of Letters Patent. Patented Jan. 16, 1917.

Application filed May 24, 1915. Serial No. 30,008.

To all whom it may concern:

Be it known that I, JOSEPH W. DAWSON, a citizen of the United States of America, a resident of the city of St. Louis, State of Missouri, have invented certain new and useful Improvements in Bottle-Washing Apparatus, of which the following is a full, clear, and exact description, reference being had to the accompanying drawings, forming a part of this specification.

My invention relates to improvements in bottle washing apparatus, one of the objects being to economize in the use of water by circulating the water from one bottle washing device to another in such manner that the efficiency of the apparatus will not be materially impaired by re-using the water.

Another object is to produce a simple automatic means for controlling the flow of water to the different washing devices.

With the foregoing and other objects in view the invention consists of the novel construction, combination and arrangement of parts hereinafter more specifically described and illustrated in the accompanying drawings wherein is shown the preferred embodiment of the invention, but it is to be understood that changes, variations and modifications can be resorted to which come within the scope of the claim hereunto appended.

Figure I is a side elevation of a bottle washing apparatus embodying the features of my invention, a portion of one of the machines being broken away to show the bottle washing devices. Fig. II is a section taken approximately on the line II-II, Fig. I. Fig. III is an enlarged section taken approximately on the line III-III, Fig. I. Fig. IV is a section taken on line IV-IV, Fig. III. Fig. V is a section taken on line V-V, Fig. III. Fig. VI is a section on line VI-VI, Fig. III.

To illustrate the preferred form of the invention, I have shown three bottle washing devices, adapted to perform successive washing operations. For the sake of convenience in describing the invention, I will term the bottle washing devices "primary", "intermediate", and "final" washing devices, but it is to be understood that the bottles may be subjected to a washing operation before being delivered to the primary washing device, or after passing from the final washing device.

P designates the primary bottle washing

device, located at the left side of Fig. I. This device is adapted to wash the outer faces of the bottles as will be hereinafter described. The intermediate washing device includes long nozzles or spindles I 60 adapted to discharge water into the bottles, and the final washing device includes nozzles or spindles F also adapted to discharge water into the bottles.

The bottles to be washed by the different 65 bottle washing devices pass from a runway 1, at the left side of Fig. I, to the primary washing device P, and thereafter the bottles are discharged onto a runway 2 whereby they are conducted to bottle receiving 70 pockets 3. These pockets form part of a traveling bottle carrier which conveys bottles to points immediately above the long nozzles I and F, and after being subjected to the action of the water which passes from 75 said nozzles, the bottles are finally discharged onto a runway 4 at the right hand side of Fig. I.

The primary washing device P comprises 80 a housing 5 mounted on a reservoir 6, and a rotary bottle holder R arranged in said housing 5. The bottle holder R comprises a series of radial pockets 7 adapted to receive the bottles as they pass from the runway 1, and adapted to hold the bottles during the primary washing operation. Any suitable means may be utilized to drive the rotary bottle carrier R, the object being to carry the bottles from the runway 1 to a water distributing device D, thereafter discharging the bottles onto the runway 2. The water distributing device D includes a manifold 8 provided with discharge members 9 (Figs. I and III) from which water is discharged onto the bottles in the rotary 90 bottle carrier R. The outer faces of the bottles are washed by the streams of water passing from the discharge members 9, and the dirt, labels, etc., pass downwardly, with the water, into the reservoir 6.

The traveling bottle carrier, whereby the bottles are conveyed from the runway 2, includes the bottle receiving pockets 3 and an endless sprocket chain 10 to which said pockets 3 are secured. The endless sprocket 105 chain 10 passes around idle wheels 12 and it is fitted to the drive wheel 13. 14 designates a gear wheel secured to the drive wheel 13, and 15 designates a pinion meshing with said gear wheel. The pinion 15 110

may be driven by any suitable power mechanism to impart an intermittent movement to the sprocket chain 10.

The final bottle washing device includes 5 the long nozzles F which are secured to manifold pipes 16, the latter being fixed to cross heads 17, see Figs. I and II. The cross heads 17 are slidably fitted to vertical guide members 18, the latter being fixed to a wall 19 of the large reservoir 20. 21 designates flexible water supply tubes leading from a manifold 22 to the pipes 16. Fresh water is forced from a water supply pipe 23 to the manifold 22, through flexible tubes 21, and 15 into the pipes 16 from which it is discharged through the long nozzles F. When the bottles are at rest immediately above the long nozzles F, as shown by dotted lines in Fig. I, the nozzles are inserted into the bottles 20 and fresh water is forced from said nozzles to thoroughly cleanse the interior of the bottles. The means for raising and lowering the nozzles F includes a link 25 pivoted to the cross head 17, and an arm 26 connected 25 to the upper end of said link, Figs. I and II. 27 designates a rock shaft secured to the arm 26, and 28 designates an operating arm secured to said rock shaft. The arm 28 is rocked, as will be presently described, to 30 raise and lower the cross head 17 and the nozzles F which move with said cross head.

The intermediate bottle washing device includes the nozzles I which have been previously referred to, water tubes 16' to which 35 the nozzles are secured, and a cross head 17' to which said water tubes are secured. The cross head 17' is slidably fitted to vertical guide rods 18'. 25' designates a short link connecting the cross head 17' to an arm 26', 40 the latter being secured to a rock shaft 27' provided with an operating arm 28'. It will be noted that the elements of the intermediate bottle washing device are quite similar to the elements of the final bottle 45 washing device, and that each of these devices is provided with an operating arm (28-28') for raising and lowering the water distributing nozzles. The arms 28 and 28' are connected to each other through the 50 medium of a connecting bar 30. 31 designates a pitman connecting the bar 30 to a crank 32, said crank being fixed to a constantly rotating power shaft 33. The crank 32 travels around the axis of the power shaft 33 so as to oscillate the arms 28 and 28', thereby raising and lowering the nozzles of the intermediate and final bottle washing devices. The intermediate bottle washing device also includes flexible tubes 55 21' leading from a manifold 22' to the tubes 16', said tubes 21' and manifold 22' being similar to the elements 21 and 22 of the final bottle washing device. I do not deem it necessary to show or describe all of the 60 details of the different bottle washing de-

vices for such details form no part of the present invention.

The means for controlling the flow of water to the different bottle washing devices includes a valve 34 for controlling the admission of water to the manifold 22 of the final washing device, a valve 35 for controlling the flow of water to the manifold 22' of the intermediate washing device, and a valve 36 for controlling the admission of water to the water distributing device D of the primary washing device. Each of these valves is provided with a bell crank lever 37 and a valve stem 38 adapted to be operated by said bell crank lever. 39 designates a link connecting the bell crank lever 37, at the primary washing device, to the similar lever 37 at the intermediate washing device, and 40 designates a link connecting the last mentioned lever 37 to the lever 27 at the final washing device. The links 39 and 40 connect the various valves with each other in such a manner that all of the valves may be opened and closed by a single valve operating device. The means for automatically opening and closing the valves includes a rocker 42 (Fig. I) and a link 43 connecting the lower end of said rocker to the link 40. The rocker 42 is pivotally supported at 44, and it is provided with a pair of jaws 45 which embrace a cam 46. This cam is fixed to the constantly rotating power shaft 33 and it is fitted to the jaws 45, so as to oscillate the rocker 42, thereby opening and closing all of the valves during each revolution 95 of the power shaft.

The water discharged from the long nozzles I and F passes into the bottles and then flows downwardly into the large reservoir 20. Fresh water is introduced into the 105 nozzles F of the final bottle washing device, and this water is re-used by forcing it from the reservoir 20 to the other bottle washing devices.

50 designates an overflow pipe leading 110 from the reservoir 20 to the reservoir 6 of the primary washing device.

51 designates a suction pipe leading from the reservoir 6 to a pump 52 which discharges water into a pipe 53. The discharge 115 pipe 53 communicates with the valve 35 which controls the admission of water to the intermediate bottle washing device, and this pipe 53 is provided with a branch 54 leading to the valve 36 of the primary wash- 120 ing device.

As previously suggested, the large reservoir 20 is common to the intermediate and final bottle washing devices, the water discharged from both of said devices being 125 drained from the bottles to said reservoir 20. This water overflows into pipe 50 and is conducted to the reservoir 6 which also receives the water discharged from the primary washing device. The primary and in- 130

termidiate bottle washing devices are supplied with water which passes from the reservoir 6 through suction pipe 51, and into pump 52, which forces the water to said primary and intermediate washing devices. The reservoir 6 is provided with an overflow pipe 60.

61 designates a rotatable screening device (Figs. III and VI) consisting of a cylindrical screen member 62, and heads 63 and 64 at the ends of said screen member. A tubular journal 65, extending from the head 64, is rotatably fitted to a discharge member 66, the latter being secured to the reservoir 6. 15 The head 64 is provided with a series of ports 67 through which the water passes in flowing from the interior of the screen to the suction pipe 51.

68 designates a shaft section connecting the heads 63 and 64, and 69 designates a drive shaft secured to a sleeve 70 which extends from the head 63. The sprocket wheel 71 is fixed to the drive shaft 69. This

sprocket wheel may be rotated continuously by any suitable mechanism. The object in 25 rotating the screen 62 is to prevent labels and other matter from accumulating on the surface of the screen.

I claim:

A bottle washing apparatus comprising a 30 device for washing the outer faces of the bottles, a water receiver adapted to receive the water which passes from said device, a pair of bottle washing devices adapted to wash the inner faces of the bottles, a reservoir common to said pair of bottle washing devices adapted to receive the water which passes from the interior of the bottles, an overflow pipe for conducting water from said reservoir to said water receiver, and 35 means for forcing water from said water receiver to one of the pair of bottle washing devices and also to the device for washing the outer faces of the bottle.

JOSEPH W. DAWSON.
